UNITED STATES PATENT OFFICE.

ROBINSON H. HARSH, OF CHICAGO, ILLINOIS.

LATCH-OPERATING MEANS.

1,279,690.

Specification of Letters Patent. Patented Sept. 24, 1918.

Application filed November 26, 1917. Serial No. 204,070.

To all whom it may concern:

Be it known that I, ROBINSON H. HARSH, a citizen of the United States, residing at Chicago, in the county of Cook and State of Illinois, have invented certain new and useful Improvements in Latch-Operating Means, of which the following is a specification.

This invention has relation to door latches, and has for an object to provide an operating means therefor, formed to resemble a human hand extended in a position to be grasped whereby to present a novel effect for advertising purposes.

Another object of the invention is to provide a door latch operating means of the nature above set forth for attachment to any door latch to operate the same.

Another object of the invention is to provide a latch operating means having the characteristics above set forth adapted for association with a door latch, of the door knob operating type, one of the knobs being removed prior to the association of the latch mechanism with my improved operating means.

In addition to the foregoing my invention comprehends improvements in the details of construction and arrangement of the parts to be hereinafter more fully described and particularly set forth in the appended claims.

In the accompanying drawings in which similar and corresponding parts are designated by the same characters of reference throughout the several views in which they appear:

Figure 1, is a view in side elevation of one form of my latch operating mechanism illustrating the door and latch in edge view.

Fig. 2, is a similar view with parts of the latch operating mechanism broken away to illustrate details.

Fig. 3, is a transverse section taken on the line 3—3 of Fig. 2.

Fig. 4, is a view in elevation with parts broken away of a modified form of my latch operating mechanism and.

Fig. 5, is a transverse section taken on the line 5—5 of Fig. 4.

With reference to the drawings, particularly Figs. 1 to 3 inclusive, 10 indicates the door having a latch mechanism embodied therein the latch bar of which is indicated at 11, and the latch lever at 12, said latch lever extending beyond both sides of the

door so as to be accessible by parties effecting either an ingress or egress.

My latch operating mechanism includes a tubular member 13, decorated or painted exteriorly to represent a coat sleeve, and hingedly mounted at one end and at the rim of the tubular member by means of a conventional type of hinge 14 whereby to permit vertical oscillation of said tubular member. The tubular member 13 is provided with an operating handle 15 formed to resemble an outstretched hand. The front of the door may be decorated, either by means of a pictorial illustration or a figure formed in relief, in which one arm is shown as a continuation of the tubular member 13 so as to present a novel effect for advertising purposes. The hand 15 will thus appear to be a part of the figure shown on the door.

The lower wall of the tubular member 13 interiorly is formed with a longitudinally extending casing 16 containing a light coil spring 17, and a bar 18 extends into said casing, the other end of the bar being pivotally connected as at 19 to the door. The spring 17 within the casing thus bears at one end against the bar 18 and at its outer end against the casing whereby to normally retain the tubular member in a horizontal position but to permit said tubular member to be depressed against the tension of said spring. A semi-circular shield 20 is secured to the door to extend around the lower half of the tubular member 13, whereby to close the gap which occurs owing to the manner in which the inner end of the tubular member 13 is cut away to permit its downward movement.

Depending from the top wall of the tubular member 13 interiorly thereof is a casting or the like 21, having a pair of spaced ears 22 formed thereon to engage opposite sides of the operating lever 12, an abutment 23 being formed on said casting to engage the upper side of said lever.

From the foregoing it will be apparent that if the handle 15 is grasped and depressed as though in the act of shaking hands, the latch lever 12 will be likewise depressed, motion of the tubular member 13 being transmitted through the casting 21 and the latch bolt 11 will be withdrawn from engagement with its keeper to permit the door to be opened.

I have illustrated in Figs. 4 and 5 a

modified form of my invention which however includes the parts numbered 13 to 20 inclusive. This form of my invention is designed for association with the type of door 5 latch embodying a rotatably mounted shank 24 having a door knob on each end. For the purposes of my invention one door knob is removed and a collar 25 substituted therefor, which is embraced about the shank and secured thereto. The collar 25 is formed with a radial pin 26. Depending from the upper wall interiorly of the tubular member 13 is an arm 27 which is offset so as to dispose its lower end to one side of the longitudinal center of said tubular member, and said lower end of the arm 27 is bifurcated as indicated at 28 so as to engage opposite sides of the pin 26.

In the operation of this form of my invention it will be seen that if the handle 15 is grasped so as to depress the tubular member 13 or oscillate the same, the vertical movement of said tubular members 13 which is in a single plane is converted into rotary 20 motion of the revolvably mounted shank 24 by means of the arms 27 and the collar and pin connection 25 and 26.

While I have illustrated and described my invention with some degree of particularity, 30 I realize that in practice various alterations thereover may be made, and I therefore desire to reserve the right and privilege of changing the form of the details of construction, or otherwise altering the arrangement of the correlative parts, without departing from the spirit of the invention or the scope of the appended claims.

Having thus described my invention what I claim as new and desire to secure by Letters Patent is:—

1. In combination with a door latch including a latch operating handle, of a tubular member, means hingedly connecting the

tubular member to the door, a casing within the tubular member, a spring within the 45 casing, a bar pivotally connected to the door and having one end extending into the casing, a handle on said tubular member in the shape of a human hand, and an operating connection between said tubular member and the latch operating lever. 50

2. In combination with a door and door latch, including an operating handle, of a tubular member, means for hingedly connecting one end of the tubular member to the door, resilient means for normally retaining the tubular member in a substantially horizontal position, an operating handle for said tubular member in the form of a human hand, a casting secured interiorly 60 to the tubular member, a pair of spaced ears on said casting to engage opposite sides of the latch operating means, and an abutment on said casting to engage the upper side of the latch operating lever. 65

3. In combination with a door and door latch including a revolvably mounted shank, a collar secured thereto, a radial pin on said collar, a tubular member, means for hingedly mounting one end of the tubular 70 member upon the door, an arm within the tubular member and movable therewith, one end of the arm being bifurcated to engage opposite sides of the pin, means for normally retaining the tubular member in a substantially horizontal position, and an operating handle on the tubular member which is shaped to conform to the shape of a human hand. 75

In testimony whereof I affix my signature 80 in presence of two witnesses.

ROBINSON H. HARSH.
